(57) **CLAIM**

The ornamental design for a thermal cycler housing, as shown and described.

DESCRIPTION

FIG. 1 is a front perspective view of a first embodiment showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof with the cover open;

FIG. 10 is a front prospective view of a second embodiment showing our new design;

FIG. 11 is a bottom perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a front perspective view thereof with the cover open.

The broken lines are for the purpose of illustrating portions of the thermal cycler housing that form no part of the claimed design.
